Primary Examiner — Caron D Veynar*Assistant Examiner* — Mehri Bajoul(74) *Attorney, Agent, or Firm* — Umberg Zipser LLP(57) **CLAIM**

I claim the ornamental design for a scent cartridge, as shown and described.

DESCRIPTION

FIG. 1 is a perspective view of the scent cartridge of the new design,

FIG. 2 is a front elevation view thereof;

FIG. 3 is a rear elevation view thereof;

FIG. 4 is a right side elevation view thereof, the left side elevation view being a mirror image of the right side elevation view; and,

FIG. 5 is a bottom plan view thereof, the top plan view being a mirror image of the bottom plan view.

In the drawings, the broken lines represent portions of the article that form no part of the claimed design.
